UNITED STATES PATENT OFFICE.

GAETANO MARCHESEINI, OF NEW YORK, AND CARLO DALBONI, OF STATEN ISLAND,
NEW YORK.

CAPPING DEVICE.

Application filed June 11, 1924. Serial No. 719,430.

To all whom it may concern:

Be it known that we, GAETANO MARCHESEINI and CARLO DALBONI, subjects of the King of Italy, residing at New York and Staten Island, in the counties of New York and Richmond and State of New York, respectively, have invented certain new and useful Improvements in Capping Devices, of which the following is a specification.

Our invention relates to capping devices, particularly devices for capping storage vessels and similar containers.

An object of this invention is to provide a device for affixing caps to cans and the like, without the use of solder, and in a manner that affords a perfect seal between the cap and the can receiving it. The advantages of the invention will appear from the following description, taken with the accompanying drawings, which illustrate how the invention may be practiced.

On said drawings,

Figure 1 shows the top, in part, of a can or vessel having a cap attached according to our invention;

Fig. 2 is a side view of such a cap;

Fig. 3 is a section on the line 3—3 of Fig. 1;

Fig. 4 shows in part the top of the can and the structure of the opening into which the cap or closure is placed;

Fig. 5 is a side view; Fig. 6 a front view; and Fig. 7 an end view of one form of our improved capping device;

Fig. 8 is a side view of another construction for achieving the objects of our invention; and

Fig. 9 is a side view, Fig. 10 a top view, and Fig. 11 a bottom view of a chuck, with controlling lever, to be mounted in said construction, and constituting another type of capping device according to our invention.

The same numerals identify the same parts throughout.

We show at 1 a container, such as a can of sheet metal, having an opening 2, through which the container can be filled with a liquid to be stored therein. This opening is adapted to be closed by a cap 3. The aperture 2 has an upturned external rim 4, and surrounding this rim is a groove 5 in the outer surface of the top of the can, forming on the inside of the can an annular rib 5^a, which reinforces the top around the opening 2. To close the opening 2, the

cap 2 has the shape of a disk, with an upturned rim 6, the edge of which is outturned to make a flange 7, that will overlap the rim 4 when the closure is inserted in the opening 2. The closure is stamped or otherwise worked to provide projections 8 on its periphery, and the rim 4 of the opening 2 has corresponding recesses 9. When the closure 3 is inserted into the opening, the projections 8 thereon fit into the recesses 9, and thus the cap is held against turning. The cap can then be worked to expand the rim 6 on the inside of the can, as indicated at 10. Thus the edge or periphery of the opening is thus firmly engaged by the cap, being held in fact between the bulge 10 and the flange 7; and the closure is thus affixed to the can and the utmost tightness of the closure is assured.

To produce the bulge 10, the device shown in Figures 5, 6 and 7 may be utilized. This device is portable and can be operated entirely by hand. It comprises a pair of bars or members 11, of suitable shape, connected adjacent one end by a pivot 12. Upon the end nearest this pivot each bar carries a semicircular die 13, the two dies being in the same transverse plane, and having their straight or diametral sides adjacent to each other. The faces of the dies are flat, and flush with each other, and the opposite curved edges of the dies are equipped with projecting flanges 14. At the other end each bar has a transverse handle 15, rigidly secured in any suitable way. These handles may be semi-cylindrical, with their flat faces turned towards each other, and between the handles are springs 16, tending to force the handles apart. These springs may be disposed in sockets. The springs keep the adjacent straight sides of the dies 13 close together, but if the handles are grasped and moved towards each other, the dies are separated.

Hence to affix a cap to the can 1 with this device, the cap is inserted into the opening 2, with the projections 8 engaging the recesses 9, to keep the cap from turning. Then the dies 13 are placed against the depressed face of the cap, and the handles 15 compressed and forced to move towards each other and thus distend the dies 13. This operation makes the flanges 14 press against the upturned rim 6, and then by rotating the entire device with the handles still com-

pressed, the rim of the cap inside the can is expanded to make the annular bulge 10. The formation of the bulge causes the cap to be drawn down somewhat, and the flange 7 thereon to press against the upper edge of the rim 4, very tightly, giving a leak-proof union that is sealed to virtually the same degree as if solder were employed.

In the remaining views of the drawings, numeral 17 indicates a standard carrying a support or rest 18 for the can to be capped. Above the rest is a vertical bearing 19, in which is a shaft 20. The lower end of this shaft, just above the rest 18, has a recess or bore 21 to receive and hold the shank 22 of a chuck 23. This chuck carries a number of levers or pivoted bars 24, similar to the bars or levers 11, mounted on pivots or journals 25. These levers are disposed in slots 26, between longitudinal ribs 27 on the chuck, and the ends of the levers each have a die 28 in the form of a roller mounted on a pivot 29. The edges or rims of the rollers may be rounded (like the flanges 14). Each lever 24 is formed like a bell crank lever, with the bend or elbow 30 turned towards the axis. Therefore, pressure on these corners along the axis will distend the levers and move the dies 28 outward.

The chuck 23 has a shoulder 31 at the juncture of the shank therewith. On this shoulder rests a ring 32 encircling the shank to press against the elbows 30 of the levers 24. On this ring is a second ring 33, carrying anti-friction balls 34, in recesses therein, and resting on this second ring 33 is a third ring 35, loosely encircling the shank 22. To the outside of this sleeve is pivoted, at diametrically opposite points the forked or yoke-end 36 of a controlling lever 37, having a handle 38. This lever carries cam projections 39 adjacent the pivots and bearing on the upper ring 32. At the upper end of the sleeve 35 is a second ring 33 with antifriction balls to encircle the shank 22 above the sleeve 35, between the chuck 32 and shaft 20. At 40 is shown a screw or key to hold the shank 22 in the bore 21 of the shaft 20; this screw entering a longitudinal slot 41 in the shank 22.

To make use of this construction, a can is placed on the rest 18, and the cap put into the opening 2. The chuck 23 and shank 22 are raised slightly as permitted by the slot 41, and then the chuck is lowered against

the closure 3. By pressing down on the lever 37, the levers 24 are distended and caused to press the dies against the rim 6 of the cap. Then, on the rotation of the shaft 20, the cap is expanded to form the bulge 10 in the cap as before.

The rings 32 and 33 and sleeve 35 have enough play on the shank 22 to permit the elbows 30 to project a little through the upper ends of the slots 26, above the shoulder 31. When the lower end of the chuck 23 is caused to engage the cap 2, the levers 24 can be moved by hand in towards the axis 70 of the chuck, and with the controlling lever 37 elevated, this movement of the levers is allowed. As soon as the lever 37 is depressed, the cams 39 force the lower rings 32 and the ring 33 down, and the levers 24 are then swung outward.

The standard 17 has lugs 43 bearing a binding screw 44 to enable the apparatus to be fastened to a bench. On the shaft 20 are fixed collars 45 above and below the bearing 19, and at the upper end of this shaft is a bevel gear 46. The bearing 19 is extended to form a horizontal bearing 47, in which is a shaft having a bevel pinion 48 at one end to mesh with the gear 46, and at the other end a crank 49 with a handle 50. By this crank the shaft 20 and chuck 23 can be rotated. As the shaft and chuck are rotated, the handle 38 can still be held and forced down because the sleeve 35 is loose on the shank 22, and because of the pressure of the bearing balls 34.

We, of course, reserve the right to make changes within the scope and spirit of the invention.

Having described our invention, what we believe to be new and desire to secure and protect by Letters Patent of the United States is:

A capping device comprising a chuck, pivoted levers on the chuck, roller dies carried by said levers, a shank connected to the chuck, a sleeve on the shank, a handle carrying cams, a ring engaged by the cams, whereby, on actuation of the lever, the dies will be moved to operative position, a shaft to rotate the shank, means to operate the shaft, a standard to support the shaft, said means and the chuck, and a rest beneath the chuck.

In testimony whereof we affix our signatures.

GAETANO MARCHESINI.
CARLO DALBONI.
